DESIGN FOR A COMBINATION SOUND AND MOTION PICTURE CABINET

Sol Freedman, Los Angeles, Calif.

Application April 29, 1940, Serial No. 92,016

Term of patent 3½ years

To all whom it may concern:

Be it known that I, Sol Freedman, a citizen of the United States and a resident of the city of Los Angeles, in the county of Los Angeles, and State of California, have invented a new, original, and ornamental Design for Combination Sound and Motion Picture Cabinet, of which the following is a specification, reference being had to the accompanying drawing, forming part thereof.

In the drawing:

Fig. 1 is a perspective view of a combination sound and motion picture cabinet showing my new design,

Fig. 2 is a top plan view thereof.

The rear of the cabinet and the side opposite to that shown are substantially plain.

I claim:

The ornamental design for a combination sound and motion picture cabinet, substantially as shown and described.

SOL FREEDMAN.
